UNITED STATES PATENT OFFICE.

GEORGE E. SHARPE, OF STEUBENVILLE, OHIO.

GAS-BURNER.

1,398,470.

Specification of Letters Patent. Patented Nov. 29, 1921.

Application filed October 18, 1920. Serial No. 417,683.

To all whom it may concern:

Be it known that I, GEORGE E. SHARPE, a citizen of the United States, residing at Steubenville, in the county of Jefferson and State of Ohio, have invented certain new and useful Improvements in Gas-Burners, of which the following is a specification.

This invention relates to improvements in gas burners of that type primarily intended for use in fire places and open face stoves and the like wherein the flames are directed against a backing lined with radiant material or the like.

One object of the present invention is to provide a burner of the above mentioned class wherein more perfect combustion is secured by admitting air at the point of combustion through the center of the flame and burner, producing an odorless fire.

Another feature of the invention resides in the particular manner of forming the burner with tubes concentric with the burner outlets and which serve to admit the air as above described.

In the drawings:

Figure 1 is a vertical section transversely of a fire place embodying the burner forming the subject matter of the present invention,

Fig. 2 is a longitudinal section of the burner,

Fig. 3 is a top plan view,

Fig. 4 is a section on the line 4—4 of Fig. 2,

Fig. 5 is a side elevation of a slightly modified form of burner,

Fig. 6 is a section on the line 6—6 of Fig. 5,

Fig. 7 is a vertical section longitudinally through the gas nozzle,

Fig. 8 is a perspective view of the gas nozzle support or elbow.

In detail:

The burner, as shown in Figs. 1 to 4 inclusive, comprises a body A consisting of end walls 1 and 2, bottom wall 3, and top wall 4, the latter having a series of burner bosses 5 spaced therealong and which are drilled or reamed to provide openings of the proper size as indicated at 6 and which communicate with the chamber B formed by the walls previously mentioned. The bottom wall 3 is apertured, as indicated at 7, such apertures alining with the openings 5 in the bosses 5 and being of slightly smaller

size and receiving tubes 9 which, by reason of their smaller size, leave a ring opening 6 previously mentioned and which forms the opening for the escape of the gas from within the chamber B. The chamber B is supplied with gas mixed with air through the medium of risers 10 which are integral with the body B and also with a body C forming a header 11 provided with a centrally located boss 12 having the opening 13 which communicates with the passage 14 of an elbow 15 having a flange 16 secured to the boss 12 by means of screws or the like 17. A gasket 18 may be interposed between the boss 12 and the flange 16 to provide a tight joint, the said flange having an annulus seating within a suitable counter-bore in the boss 12. The elbow 15 is provided with a bell mouth 19 and is hung by a screw 20 entering a spot 21 cast integrally with the header 11. Parallel arms 22 are drilled as at 23 to receive screws securing the gas nozzle in place, as will be hereinafter described.

The combined gas nozzle and valve as indicated in general at D (see Fig. 7) comprises a body portion 24 having arms 25 provided with holes 26 through which screws pass for the purpose of mounting the gas nozzle D on the arms 22. A valve body 27 having a tapered bore receives the valve element 28 which is secured in place by a washer and screw at the one end and carries a stop pin 29 engaging with the abutments 30 to prevent the valve element 28 from turning so far around as to render its cut-out portion 30' ineffective. A screw 31 extending into the squared recess 32 provides for fastening a turning key 33 in place. The gas line or supply 34 is connected with the threaded end 35 while the upper end of the body 24 carries the tubular member 35' threaded at one end as at 36 on the exterior to receive a cap nut 37 and on the interior to receive the threaded head 38 of the needle valve 39, a knurled thumbpiece 40 being provided for rendering adjustment easy. The forward end of the tubular member 35' is also threaded on the exterior to receive a baffle flange 41 which is adjustable back and forth between the arms 22 to regulate the amount of air taken in through the passage 14 and mixed with the gas. On the interior the forward end of the tubular member 35 is threaded to receive a nozzle tip 42 having 110

a conical recess 43 receiving the conical end 44 of the needle valve 39 and having an outlet 45 whereby the amount of gas is regulated through adjustment of the needle valve 5 by turning the knurled thumb-piece 40.

In the modification of the burner as shown in Figs. 5 and 6 the construction is identical with that just described except for the fact that the body 46 and the header 47 are cast 10 separate and joined by flanges 48 and 49 connected by bolts or other securing means 50, a suitable gasket being interposed between the flanges.

In the operation of the burner the needle valve 39 is adjusted to feed the proper amount of gas and the baffle 41 is regulated for the proper amount of air at this point. The air and gas are thus mixed in the passage 14 and travel through the header C 20 and risers 10 to the chamber B and escape through the circular orifices 6 where they are burned, additional air being taken in directly at the point of combustion through the members 9, thus insuring absolutely complete combustion of even the most inferior 25 grades of gas.

I claim:

1. The combination in a gas burner, of a longitudinal head having alining burner 30 openings in a horizontal plane, means for supplying a combustible mixture to the openings including spaced risers leading into the bottom of the head and associated with gas mixing means, and means for supplying an 35 additional quantity of air at the interior of

the zone of combustion of each burner opening.

2. The combination in a gas burner, of a longitudinal head having burner openings, auxiliary air supply means centrally of these 40 openings, means for distributing a combustible mixture uniformly to such openings and including a riser approximate each end of the head, and gas mixing means associated with said distributing means. 45

3. In a gas burner, the combination of a hollow body having alined openings extending longitudinally of its upper and lower walls, the openings in the lower wall of the body being of less diameter than the openings in the upper wall thereof, open-ended air conducting tubes fitted snugly in the openings in the lower wall of the body and extending across the body and into the openings in the upper wall thereof, gas-conducting risers communicating with the interior of the body adjacent the ends thereof, a header connecting the lower ends of said risers, an elbow secured to the said header and communicating therewith through the bottom of the same, a tubular gas supplying body carried by the outer end of said elbow and discharging into the same, regulating devices disposed within said gas-supplying tubular body, and a baffle secured upon said 65 body and adjustable longitudinally thereof toward and from the outer end of the elbow.

In testimony whereof I affix my signature.

GEORGE E. SHARPE. [L. S.]
